UNITED STATES PATENT OFFICE.

WILLIAM S. ATWOOD, OF MONTREAL, QUEBEC, CANADA.

TREAD-PLATE.

1,193,857.

Specification of Letters Patent.

Patented Aug. 8, 1916.

Application filed January 14, 1915. Serial No. 2,178.

To all whom it may concern:

Be it known that I, WILLIAM S. Atwood, a citizen of the Dominion of Canada, and resident of the city of Montreal, in the Province of Quebec and Dominion of Canada, have invented certain new and useful Improvements in Tread-Plates, of which the following is a full, clear, and exact description.

10 This invention relates to improvements in tread plates, and the object of the invention is to produce a metal tread plate of the apertured type having the apertures so guarded that all possibility of accident resulting 15 from persons inserting umbrellas, canes and the like through the apertures will be precluded.

The device consists essentially of a plate, preferably of rolled sheet metal, having apertures therein formed by making cuts in 20 the plate and slightly depressing the material inclosed by the cuts. The metal around the opening thus formed is turned upwardly.

25 In the drawings which illustrate the invention:—Figures 1 and 2 are partial plan views of a tread plate showing different aperture arrangements. Fig. 3 is a front elevation of a plate. Fig. 4 is an enlarged plan view of a single aperture. Fig. 5 is a section on the line 5—5, Fig. 4. Figs. 6 and 7 are plan views showing slight modifications of shape. Fig. 8 shows a slight modification.

35 Referring more particularly to the drawings, 11 designates a plate of suitable material, preferably rolled sheet metal, which may be provided with flanges 12 if desired, arranged in any suitable manner. The 40 plate is provided with a multitude of small tongues or lugs 13 formed integral therewith by making curved or angular cuts in the plate. The portion of metal inclosed by each cut forms a tongue and is bent 45 slightly downward, as clearly shown in Fig. 5, so as to form an aperture 14 in the plate. The metal surrounding the aperture adjacent the free edge of the tongue is bent upwardly, as shown at 15, to provide a gripping surface upon which a person's foot 50 will not readily slip.

In Figs. 1 to 4, the tread plate has been shown with an aperture formed by an arcuate cut of about 240°. The invention is by 55 no means limited to this particular form, as

arcuate cuts much shorter may be used, as shown in Fig. 6, wherein the cuts separating the two tongues 13^a are less than semi-circular, and are in fact equal arcs described from a common center. In Fig. 7, the cut 60 is angular in form producing a pointed tongue 13^b. Figs. 1 to 6 show the result produced by making the single cut, Fig. 7 by making two meeting cuts, while Fig. 8 shows the same result produced with two 65 cuts which do not meet but separate a strap 16 attached to the plate at its ends and depressed at its central portion, forming an elongated aperture. The long edges of the aperture are turned up as previously described to form the gripping portions 15. It is obvious that many other shapes may be used, as desired, and also that the arrangement of the tongues in the plate may be of any suitable form, as indicated by the difference between Figs. 1 and 2.

It will be readily understood that this invention is an improvement on my former patent applications, Ser. Nos. 871,055, 872,584 and 872,585. These inventions show 80 tread plates adapted to particular and to more or less general purposes. It has been discovered, however, that tread plates with apertures entirely through are a source of danger in the steps of street railway cars or 85 anywhere where they will be used by the general public, who are liable to accidentally or otherwise insert umbrellas, canes or the like through the plate apertures, with possibly disastrous results. In the present invention, an edge is formed in the plate which may be turned up to provide the required tread surface, as in the former patent applications. The tongue closes the aperture sufficiently to prevent the catching of 90 an umbrella or cane therein, but yet leaves a sufficient space for the escape of water.

Having thus described my invention, what I claim is:—

1. A device of the character described, 100 comprising an apertured plate having a portion of the periphery of each aperture upwardly turned, and a tongue preventing passage through the aperture in a direction perpendicular to the plate.

2. A device of the character described, 105 comprising an apertured plate, ridges or bosses partially surrounding each aperture formed by upward displacement of the metal at the edge of the aperture, and 110

tongues below the apertures integral with the plate and formed by downward displacement of the metal removed from the apertures.

5 3. A tread plate comprising an apertured metal sheet having a portion of the metal at the edge of each aperture upwardly turned through an acute angle, and the metal dis-

placed in formation of the aperture downwardly turned through an arcuate angle. 13

In witness whereof, I have hereunto set my hand, in the presence of two witnesses.

WILLIAM S. ATWOOD.
